No. 694,460.

Patented Mar. 4, 1902.

B. J. CASTERLINE.
STOVE DAMPER REGULATOR.

(Application filed July 27, 1900. Renewed Aug. 1, 1901.)

(No Model.)

UNITED STATES PATENT OFFICE.

BARNABAS J. CASTERLINE, OF OLALLA, OREGON.

STOVE-DAMPER REGULATOR.

SPECIFICATION forming part of Letters Patent No. 694,460, dated March 4, 1902.

Application filed July 27, 1900. Renewed August 1, 1901. Serial No. 70,501. (No model.)

To all whom it may concern:

Be it known that I, BARNABAS J. CASTERLINE, a citizen of the United States, and a resident of Olalla, county of Douglas, and State of Oregon, have invented certain new and useful Improvements in Stove-Damper Regulators, of which the following is a specification, reference being had to the accompanying drawings, forming a part thereof, in which similar letters of reference indicate corresponding parts.

This invention relates to improvements in stove-damper regulators.

The nature and object of the invention will be fully understood from the following general description and the annexed drawings and will be subsequently pointed out in the claim.

Referring to the accompanying drawings, which are hereby made a part of this specification, Figure 1 is a view of a stove in elevation with my invention attached hereto. Figs. 2 and 3 are detail views of different parts more fully described.

25 A designates a stove, which may be of any approved construction.

B designates an air-tight air-chamber, which may be located against the wall of the room in which the stove sits, near the ceiling. In this 30 chamber are placed divers upright conical tubes b with their larger ends down.

C designates a cylinder located in the side wall of the chamber B and communicating with the interior thereof. A piston C' works 35 in this cylinder. The outer head of this cylinder is pierced with the screw c², which is hollow and embraces the piston-rod c throughout the whole length of said screw. Between the piston-head C' and the screw c² is placed 40 the helical spring C², embracing the piston-rod c. The tension of this spring C² may be regulated by turning the screw c². The piston C' is free to be acted upon by pressure from within the chamber B.

45 d is a pitman, which is interposed between the piston-rod c and the crank-handle d' of the stovepipe-damper. This pitman is pivotally connected with both the piston-rod and the damper-crank. To the outer end of this 50 pitman is also pivotally attached the rod e. At its connection with the pitmen this rod e is slightly slotted to allow for the motion to

be hereinafter described. To the lower end of this rod e is pivotally connected the rod e', which is supported in upright position by the 55 ear e². The lower end of this rod e' is pivotally connected with the upper end of the short rod e⁴ by the joint e³. The lower end of the rod e⁴ is pivotally connected with the crank i. The shaft I is journaled in suitable bearings 60 on the stove A. On this shaft are mounted the cranks i and i'. The crank i is connected with the rod e', as before described. The crank i' is pivotally connected with the stove-draft damper a at i². 65

In the example of my invention here given I have illustrated a sliding damper; but it is evident that a damper of any other approved form might, with a slight alteration of the connecting mechanism, be made to serve 70 equally as well.

All the various parts of the mechanism are to be substantially as illustrated in the drawings.

To use my invention, the various parts are 75 to be placed in their proper positions and properly connected, as illustrated in the drawings. A fire is then lighted in the stove. As soon as the air in the lower portions of the room about the stove grows warm it will rise 80 upward toward the ceiling, passing partly through the tubes b. The warm air passing through these tubes will heat the air confined in the chamber B. This confined air so heated will press upon the face of the piston C' and 85 cause it to move outward, compressing the spring C² and carrying with it the piston-rod c, which in its turn moving the pitmen d, and the crank d' closes the damper of the stove-pipe. At the same time that the stove-pipe 90 damper is thus closed the rods e and e' by reason of their connections, as hereinafter described, are raised a little. This turns the crank i, the shaft I, and the crank i'. This crank i' by reason of its connection with the 95 draft-damper a causes it also to close, and thus by the outward motion of the piston C' the pipe-damper and the draft-damper are simultaneously closed. As soon as, on account of the dampers being closed, the heat 100 decreases, the pressure in the chamber B will also decrease. Then the spring C² will by its resilience force back the piston toward its original position, and by so doing will re-

verse the motion just described and open both dampers simultaneously. In this way both the dampers may be simultaneously regulated, so as to maintain a uniform heat in the room as long as the supply of fuel lasts in the stove.

What I claim as my invention, and desire to secure by Letters Patent, is—

1. The combination with a stove, the pipe thereof, a damper in said pipe, and a crank actuating said damper, of an air-chamber, conical tubes vertically arranged in said chamber, a cylinder in the wall of said chamber, a piston and piston-rod in said cylinder, a screw and spring embracing said piston-rod in said cylinder, a pitman pivotally connecting said piston-rod, and said damper-crank, all substantially as and for the purpose set forth.
2. The combination with a stove and the pipe thereof, the draft-damper of said stove, a damper in said pipe, and a crank actuating

said damper, of an air-chamber, vertical tubes in said air-chamber, a cylinder in the side wall of said chamber, a piston and piston-rod in said cylinder, a screw and a spring embracing said piston-rod in said cylinder, a pitman pivotally connecting said piston-rod and said damper-crank, a shaft journaled on said stove, cranks mounted on said shaft, two pivotally-connected rods, connecting one of said cranks with said pitman and said damper-crank, and the other crank on said shaft connected with the said draft-damper of said stove, all substantially as and for the purpose set forth.

In testimony that I claim the foregoing as my invention I have signed my name, in presence of two witnesses, this 10th day of July, 1900.

BARNABAS J. CASTERLINE.
